PAGE 2

Fig. 2

Fig. 3

Fig. 4

Fig. 6

FIGURE 1 is a perspective of a bag stretcher or similar article showing our new design;

FIGURE 2 is a top plan view thereof;

FIGURE 3 is a side elevational view thereof;

FIGURE 4 is an opposite side elevational view thereof;

FIGURE 5 is a front elevation view (head end) thereof; and

FIGURE 6 is a rear elevational view (tail end) thereof.

The broken line showing of four demountable stretching fingers in FIGURE 1 and of an operating cable in all the figures, is for illustrative purposes only.

We claim:

The ornamental design for a bag stretcher or similar article, substantially as shown and described.
